UNITED STATES PATENT OFFICE.

WALTER T. YOUNG, OF WEISER, IDAHO.

ROTARY INTERNAL-COMBUSTION ENGINE.

Application filed April 17, 1922. Serial No. 553,346.

To all whom it may concern:

Be it known that I, WALTER T. YOUNG, a citizen of the United States, residing at Weiser, in the county of Washington and State of Idaho, have invented certain new and useful Improvements in Rotary Internal-Combustion Engines, of which the following is a specification, reference being had therein to the accompanying drawings.

10 This invention relates to a rotary internal combustion engine and it has for its object to provide an improved device of this character which will operate with certainty and economy and will present many 15 advantages over the reciprocating internal combustion engines now commonly employed. An engine constructed in accordance with the invention will be practically free of vibration, will be of light weight in 20 proportion to the power generated, will be more economical to construct and maintain and will readily lend itself to the addition of other units as the power requirements vary.

25 Further objects and advantages of the invention will be set forth in the detailed description which follows.

In the accompanying drawings:

Fig. 1 is a perspective view of an engine 30 constructed in accordance with the invention;

Fig. 2 is a view with one side of the casing removed and with certain of the parts in section.

35 Fig. 3 is a transverse sectional view through the cylinder, water jacket, piston and web of one of the engines;

Fig. 4 is a horizontal sectional view upon line 4-4 of Fig. 1; and Fig. 5 is a vertical 40 sectional view on line 5-5 of Fig. 2.

Fig. 6 is a detail sectional view of a packing ring hereinafter described.

Like numerals designate corresponding parts throughout the several figures of the 45 drawing.

A complete engine may comprise as many units as is desired, said units having a common main shaft 5 and each unit comprising an annular cylinder 6, water jacket 7, exhaust conduit 8, combustion chamber 9 and compression chamber 10. Discs 11 secured to the main shaft 5 in the several units are provided with radial heads 12 which project into the annular cylinders 6 and are 50 provided with pistons 13 which fit snugly 55 within the annular cylinders and are pro-

vided with packing rings 14. Laterally movable abutments 15 and 16 are movable to and from positions where they span the annular cylinder, said abutments being carried by stems 17 and 18, respectively. The abutments are forced inwardly by springs 19 and move outwardly against the tension of said springs by levers 20 and 21. The outer ends of these levers bear upon rollers 22 and 23 carried by the stems 17 and 18. These levers are pivoted intermediate their ends at 24 and 25 in brackets 26 which project laterally from stiffening ribs 27 of the casing 28 of the engine. The inner ends of 70 these levers 20 and 21 are acted upon by a cam face upon a cam 29, said cam being mounted upon the main shaft 5. This main shaft also carries, for each engine, (though only one is shown), a crank 30, which through a joint 31 and rod 32 locks a lever 33 upon its pivot 34 in an arm 35 of the engine casing. The lever 33 is connected to a piston rod 36, which carries a piston 37, movable in the compression chamber 10. A 80 fuel supply pipe 38, which may lead from a carburetor or other source of fuel supply is provided with branches 38^a and these branches communicate with the lower portions of the compression cylinders 10 of the 85 several units. Each compression chamber 10 is provided with an inlet valve 39 which opens inwardly and permits the fuel, which may be carbureted air from a carburetor, to be drawn past said valve into the compression chamber when the piston 37 moves outwardly in said chamber. When the piston 37 moves inwardly in said chamber, a check valve 40 opens and permits the passage of the fuel into an explosion chamber 95 41. Laterally movable valves 42 control the communication of the explosion chamber with the annular cylinder 6 and this valve is actuated in the same manner that the abutments 15 and 16 are actuated, it 100 being understood that there is one of these valves for each unit and that said valves are actuated by levers 43 which correspond to levers 20 and 21 in their method of operation though the actuating cams for these 105 levers are not shown. The operation of the engine is as follows: it being understood that the operation described is the operation of one unit and that the operation of the other unit is the same and that there 110 may be as many of these units as is desired and that these several units are arranged

to receive their power impulse at different points in the cycle of rotation of the main shaft. When the pistons 13 and the heads 12 approach the abutment 15 the cam 29 acts upon the lever 21 to withdraw the abutment and permits the piston to pass. Immediately thereafter the cam releases the lever 21 and the spring of abutment 15 causes it to snap quickly to closed position. 10 The same action takes place when the heads 12 and pistons 13 approach abutment 16; that is the abutment is retracted to permit these parts to pass and thereafter the abutment immediately snaps back, the packing ring 16*, (see Fig. 6,) at this time forming a gas-tight joint for the explosion chamber. As the piston revolves about shaft 5 and moves through the annular cylinder 6, the explosive charge is forced into the explosion chamber 41 by the piston 37 in the manner hereinbefore set forth and about the time the piston 13 reaches the point marked X, valve 42 is opened permitting the compressed charge to pass into the cylinder 6 20 and at the same time a spark plug of conventional form, indicated at 44, is energized and the charge is fired, driving the piston around in the cylinder 6, the charge being finally exhausted through exhaust port 8. 25 During the time that the piston 13 is moving between the abutments 15 and 16, a slight vacuum is produced in the annular cylinder 6, between these abutments and upon opening of the abutment 16 a compressed charge will be drawn quickly into the compression chamber for the next explosion. At 45 I have indicated a plurality of openings in the wall of the cylinder 6 through which oil is introduced; the oil 30 traveling down grooves 47 into a gutter 48 and being delivered thence through a port 49 to a conventional oil pump (not shown) by which it may be again introduced through the port 45. Thus the piston during its 45 travel past the gutters and ports and grooves is lubricated to a sufficient extent to supply lubrication for the remainder of its travel.

By the provision of the two abutments 15 and 16 I prevent the fouling of the space between said abutments by the exhaust gases and I insure that when the piston is passing abutment 16, no exhaust gases will find their way past said abutment 16 because, at this time, abutment 15 will be closed. Furthermore, the provision of the space between the abutments 15 and 16 protected from exhaust gases, facilitates the introduction of lubricating oil through ports 45 and to the channels 47 for the efficient lubrication of the piston. It is apparent that efficient lubrication is of vital importance in a motor of this character.

It is to be understood that the invention 60 is not limited to the precise construction set

forth but that it includes within its purview whatever changes fairly come within either the terms or the spirit of the appended claims.

Having described my invention what I claim is:

1. In a rotary internal combustion engine, the combination with an annular cylinder of a rotor and piston, the latter traveling in the cylinder, an exhaust conduit, a fixed combustion chamber projecting tangentially from the cylinder in spaced relation to the exhaust conduit, a compression cylinder at the other end of the combustion chamber, a compression piston therein, an inwardly opening check valve disposed between the compression chamber and the combustion chamber, a source of fuel supply, a check valve between the source of fuel supply and the compression chamber, a laterally acting slide valve spanning the cylinder just beyond the mouth of the exhaust port, a second laterally acting slide valve spanning the cylinder just in advance of the mouth of the compression chamber, a main shaft upon which the rotor is mounted, a crank carried thereby, a pivoted lever, means for connecting one end of said pivoted lever to the crank and for connecting the other end of said pivoted lever to the piston of the compression chamber, a cam on the main shaft having a raised portion on its side face, levers pivoted intermediate their ends with their inner ends in position to be successively engaged by said raised portion of the cam, and their outer ends engaged with the laterally acting slide valve of the cylinder.

2. An engine of the character described comprising a main shaft, a cylinder concentric therewith, a rotative element carried by the main shaft, a piston carried by said element and traveling in said cylinder, an exhaust conduit leading from said cylinder, a compression chamber disposed in the direction of travel of the piston and extending tangentially from the cylinder, a pair of laterally movable abutments adapted to span the cylinder one of said abutments being located just beyond the mouth of the exhaust conduit and the other of said abutments being located just in advance of the mouth of the compression chamber, means for retracting said abutments upon the approach of the piston, a compression cylinder having its inner end connected with the outer end of the combustion chamber, a piston traveling in said compression cylinder, means for actuating said piston and said abutments from the main shaft of the engine and a valve in the combustion chamber adjacent its point of connection with the cylinder.

3. A motor of the character described

comprising an annular cylinder, a rotor carrying a piston movable in said cylinder, an exhaust conduit leading from said cylinder, a combustion chamber associated with said cylinder, an abutment spanning the cylinder immediately beyond the mouth of the exhaust port, a second abutment spanning the cylinder in advance of the combustion

chamber, means for withdrawing said abutments to permit the passage of the piston 10 and conduits for the admission of oil, located between the two abutments.

In testimony whereof I hereunto affix my signature.

WALTER T. YOUNG.
